(57) **CLAIM**

The ornamental design for a soft tissue adhesion rupturing tool, as shown and described.

DESCRIPTION

FIG. 1 is a front elevated view of a soft tissue adhesion rupturing tool showing my new design;

FIG. 2 is a left side elevated view of the soft tissue adhesion rupturing tool;

FIG. 3 is a top plan view of the soft tissue adhesion rupturing tool;

FIG. 4 is a bottom plan view of the soft tissue adhesion rupturing tool;

FIG. 5 is a top perspective view of the soft tissue adhesion rupturing tool; and,

FIG. 6 is a bottom perspective view of the soft tissue adhesion rupturing tool.
